AIR-CONDITIONING SYSTEM AND
APPARATUS THEREFOR

Genaro A. Larriva, Tucson, Ariz.

Application October 22, 1938, Serial No. 236,486

4 Claims. (CL 62—139)

The present invention relates to air-conditioning and more particularly to a method and apparatus for conditioning air for rooms, residences and other enclosures and contemplates, as a part thereof, imparting to the air characteristics of temperature and humidity for bringing the air being conditioned within the healthful comfort range and the provision of mechanical units or means for effecting that result.

Two of the common methods for cooling air in hot and dry climates are, first, to pass the air through an air washer of high efficiency, thus cooling it by evaporation, adiabatically and, second, by mechanical refrigeration of the air. The purpose of the present invention is to cool air in such a manner as to obtain an actual temperature lower than either or both of the above assumed minimum temperatures without the aid of any external source of refrigeration.

In carrying out my invention, I take the raw (fresh) outdoor air from any point outside of the area or enclosure to be air-conditioned or a mixture of this outdoor air and conditioned air from the enclosure and cause the same to enter an apparatus embodying the invention. When required, this incoming air may be first dehydrated in order to effect and maintain an established dew-point or a dew-point equivalent to the atmospheric dew-point desired within the enclosure or area to be air-conditioned. After attaining an established dew-point, this incoming air is filtered and finally divided up into a primary stream and a secondary stream. The primary stream of air is caused to circulate into and out of thermic relation with the secondary stream without directly contacting the latter, whereby, the primary stream of air is thus cooled anhydrously and this relatively dry stream of air is solely used for cooling a given area. This secondary air stream is caused to actually flow in counter directions about said primary stream of air and is or may be divided into several supplemental streams in order that an effective counterflow may be established, whereby, one portion or a supplemental stream of this secondary air may be cooled by evaporation and brought into thermic relation with the primary stream of air for effecting the initial cooling thereof without adding moisture thereto. The remaining portions or supplemental streams of this secondary air are first pre-cooled anhydrously to reduce their dry-bulb temperature and then it is subjected to an adiabatic evaporative cooling. These so treated cooled streams of secondary air are finally brought into thermic relation with said primary

stream for further reducing the dry-bulb temperature of the latter, with the result that the primary stream of air is cooled to approximately the wet-bulb temperature of the secondary air without adding moisture thereto. Therefore, my method and means of controlling and/or producing air of any desired dry-bulb temperature with a certain wet-bulb temperature, or of a certain dew-point at a certain dry-bulb temperature, or of a certain relative humidity at a certain dry-bulb temperature, is accomplished without being limited by prevailing conditions of the outdoor air available, or relying on any external source as a cooling medium to help to bring about these results. Starting with any given conditions, and without the use of refrigeration or any available cold water supply, it is possible with my method of cooling air to produce the same economically and within one enclosure at the desired dry-bulb temperature at the desired dew-point, without limiting the dry-bulb temperature of the final leaving air to its original wet-bulb temperature, or to an artificial wet-bulb temperature brought about by cooling mediums or sources outside of the apparatus used for carrying out my invention. It is therefore another purpose of the invention to produce a method of cooling air with equally good results as that of certain expensive refrigeration systems, which may be carried out within one compact enclosure, the cost of construction of which is considerably less than the conventional cooling units now in vogue and, also, which can be operated and maintained at cost considerably less than such conventional air cooling apparatus for carrying out the functions of air-conditioning including heating, cooling, humidifying, dehumidifying, ventilation and air cleaning.

Another equally important object of the present invention is to provide a multi-stage heat transfer unit for conditioning air to the desired dry-bulb temperature without changing the moisture content thereof and which dry-bulb temperature has its lower limits solely defined by the dew-point of the air within the unit.

A further important object of the present invention is to provide a multi-stage heat transfer unit of an economical and commercially feasible construction having an extremely low cost of operation and which is composed of a plurality of correlated members in such a manner that units of any desired size may be produced by adding to or taking away some of said correlated members or the members may be readily removed and repaired or substituted for one an-

other for maintaining the unit in condition for maximum performance.

A still further object of the present invention is to provide an economical, convenient and compact multi-stage, self-regenerating, dehumidifying unit using suitable agents or chemicals for dehydrating artificially to any established or desired dew-point air to be subsequently used in conditioning a given area or enclosure, which will intermittently and automatically regenerate or 10 re-activate the dehydrating agents, whereby the latter may be repeatedly and continuously used throughout their useful life.

The further manifold objects of the invention will be in part obvious and in part pointed out 15 hereinafter.

In order that the invention and its mode of operation may be readily understood by persons skilled in the art, I have in the accompanying drawings and in the detailed following description 20 based thereupon, set out an embodiment of the same.

In the drawings,

Fig. 1 is a vertical sectional view through the main casing or housing for the apparatus embodying the present invention.

Fig. 2 is a detailed transverse vertical section on a slightly reduced scale of the apparatus shown in Fig. 1, on the line 2—2 in the direction of the arrow points.

Fig. 3 is a top plan view, partly in section, of the multi-stage heat exchange unit.

Fig. 4 is a vertical section through the heat exchange unit casing showing the latter positioned therein. The heat exchange unit is shown partly in end elevation and partly in section.

Fig. 5 is a detailed sectional perspective view of the heat exchange unit.

Fig. 6 is a detailed horizontal section through the main casing showing the dehydrating casing mounted therein, which latter is shown in section and the dehydrating unit shown partly in section and partly in elevation.

Fig. 7 is a vertical sectional view similar to Fig. 1 of a slightly modified form of the apparatus embodying the present invention.

Fig. 8 is a similar view of a slightly modified form of the invention.

Fig. 9 is a vertical sectional view through an apparatus illustrating another modification of the present invention, and

Figs. 10 and 11 also illustrate additional modifications in apparatus for carrying out the present invention.

Referring now more particularly to the accompanying drawings wherein like and corresponding parts are designated by similar reference characters throughout the several views, I have herein illustrated part of a cubical casing 1 within which is situated the entire apparatus comprising the invention. This main or outer casing 1 of the apparatus, as is better illustrated in Figures 1 and 2 of the drawings, comprises a bottom 2, side walls 3 and 4, and end walls 5 and 6, all of which normally establish an open upper end. Secured within this main casing is a heat exchange unit housing or casing comprising the end walls 7 and 8, each of which extend in a vertical direction from the bottom 2 and are arranged in spaced relation between the side walls 3 and 4 of the main casing, thereby forming a compartment in which the heat exchange unit may be arranged. Formed with or secured in any suitable manner to the walls 3, 4, 7 and 8 75

and spaced from the bottom 2 is a horizontally arranged partition 9 forming within the heat exchange housing a sump 10 and a heating chamber 11. The top 12 of the heat exchange casing has supported thereupon and connected therewith a pair of spaced vertically extending walls 13 and 14, each having its marginal or opposite edges secured to the side walls 3 and 4 of the main casing.

The side wall 3 of the main casing may have an opening formed therein for receiving a casing for housing the dehydrating unit, which latter comprises a side wall 15, as is better shown in Figure 6 of the drawings, which normally closes the opening within the side wall 3 of the main casing and extends contiguous therewith.

This dehydrating unit casing also comprises the vertical walls 16, 17 and 18, all having their inner vertical edges converging to a common center for forming a bearing 8'. The outer edge of the wall 16 is connected to the wall 15 by means of a vertical wall 19 and this latter lies within and closes an opening formed within the wall 5 of the main casing, whereas, one

edge of the wall 17 is connected by a wall 20 to the wall 15 and this wall 20 lies within and closes an opening formed within the wall 18.

The walls 15, 16, 17, 19 and 20 form a hot air chamber or duct 21, the upper end of which

converges into a smaller outlet or chimney 22, as is shown in Figure 1 of the drawings, whereas, the lower end of this duct 21 is closed by means of a bottom wall or partition having an opening therein which is in communication with the heating chamber 11 by means of the duct 23.

When this dehydrating unit casing is placed within the main casing, the walls 16 and 18 thereof, together with the walls 4 and 5 of the main casing, form an air inlet duct 24. The

wall 4 of the main casing, the wall 13 supported upon the heat exchange casing and the walls 17 and 18 of the dehydrating unit casing establish a moist air outlet duct 25. The walls 17 and 18 of the dehydrating unit casing have formed therewith a cowl 26 having fins 27 formed upon the outer surface thereof, all of which are suspended within the moist air duct 25. This moist air duct 25 has arranged therein for closing the upper end of the same, a horizontally extending

partition 28 and this latter has seated therein a casing 29 containing a wet air blower. The lower end of this casing 29 communicates with the moist air duct 25, whereas, the upper end is provided with an outlet 30 whereby the moist

air from the duct 25 may be discharged therefrom.

The walls 3, 4 and 6 of the main casing together with the wall 8 of the heat exchange unit casing and the wall 14 extending from the latter, form a conditioned air duct 31. A partition 32

which extends between the walls 6 and 8 closes the lower end of this air duct 31, whereas, another partition 33 closes the upper end of this air duct. Seated within the partition 33 is a

casing 34 housing an air blower therein and the lower end of this casing 34 communicates with the air duct 31, whereas, the upper end of this casing is provided with an outlet 35 for conducting the cooled air to the room or other area to be conditioned. The wall 18 of the dehydrating unit casing extends contiguous with the upper end of the wall 7 of the heat exchange unit casing

whereby the walls 3, 4 and 5 of the main casing, together with the wall 7, establish a duct 36, the

upper end of which is at all times in communication with the air inlet duct 24. The walls 7 and 8 of the heat exchange unit casing are provided with openings 37 and 38 respectively, whereby a passageway is established through this casing between the ducts 36 and 31. The top 12 of the heat exchange casing is provided with an opening 39 which establishes a means of communication between the interior of the heat exchange unit casing and the moist air duct 25.

Arranged within the upper end of the heat exchange unit casing is a plurality of horizontally extending spaced water troughs 40 which are to be supplied with water from a perforated sprinkler pipe 41. The water from these troughs 40 is allowed to normally flow directly through the heat exchange casing and drop by gravity into the sump 10. A float valve controlled inlet 42 permits a water level 43 to be maintained in this sump 10, whereas, an outlet pipe 44 is arranged within the sump for permitting water to be drawn therefrom to a motor driven pump 45, which latter in turn supplies the water through the pipe 46 to the sprinkler pipe 41.

The air blowers arranged within the casings 29 and 34 are driven by means of an electric motor 47 supported by the main casing and jointly connected to the driven shafts of the blowers by means of the pulley 48, whereby when these blowers are set in motion, air will be drawn in through the duct 24 through the heat exchange casing into the ducts 25 and 31 and finally discharged through the outlet openings or passageways 30 and 35. These blowers may be so arranged as when they are at rest, the outlets to the ducts 35 and 30 may be closed for a purpose which will be later described.

Extending across the duct 36 and supported at its upper end by means of the wall 7 above the inlet opening 37 of the heat exchange unit casing and its lower end being supported by means of a bracket 49 is a mat 50 containing suitable air filtering material whereby the incoming air from the duct 24 will be filtered before entering the heat exchange unit casing.

The side walls 3 and 4 of the main casing have secured thereto tracks 52 which extend horizontally from the wall 8 of the heat exchange casing to the end wall 5 of the main casing and this wall 5 may have a closure controlled opening 53 formed therein, whereby access may be gained from the exterior of the main casing of the apparatus into the interior of the heat exchange casing, whereby a heat exchange unit may be inserted into or removed from this heat exchange unit casing when it is required to clean the same or make repairs thereto.

The dehydrating unit consists of a rotatable carrier or drum 54 having its upper end opened and a perforated bottom 55, upon the latter of which is supported a plurality of containers 56 having arranged therein suitable dehydrating agents or chemicals, such as silica gel, activated alumina and like hygroscopic compositions which readily absorb and retain water and are particularly adapted for reducing to a low dew-point, air that may pass therethrough or thereon. The upper marginal edge of this carrier is provided with gear teeth 57 which mesh with a gear wheel 58 driven by an electric motor suspended from and carried by the dehydrating unit casing. Radially extending partitions (not shown) are arranged within the drum 54 for establishing therein three compartments indicated by the letters A, B and C and in each compartment there is arranged any

desired number of the containers 56 having the dehydrating agents therein. This drum 54 is supported by a shaft extending through the bearing 8' of the dehydrating unit casing, whereby during the rotation of the drum in a clockwise direction, it will pass through openings formed within the walls 16, 17 and 18 of the dehydrating unit casing. The radially extending dividing partitions arranged within the drum close the openings within the walls 16, 17 and 18 when the drum is at rest in order to prevent the escape of air or other gases from the ducts 21 and 24. An intermittent rotary movement is given this drum 54 whereby the several compartments A, B and C may at times be brought within the respective ducts 21 and 24 and the cowl 26. The section A, which is shown in Figure 6 of the drawings as being positioned within the air inlet duct 24, will, during the first intermittent rotary movement of the drum, be caused to enter the duct 21 where it is subjected to heat for drying the hygroscopic materials arranged therein and during the next intermittent rotary movement, the section A will be moved so as to be positioned within the cowl 26 where it may be subjected to a cooling treatment. During these two intermittent rotary movements of the drum, the compartment C will be caused to first move within the air inlet duct 24 and subsequently moved within the hot air duct 21 and, likewise, the compartment B will be first moved within the cowl 26 and then moved within the air inlet duct 24. This rotary intermittent movement may be transmitted thereto as often as it may be required to regenerate or reactivate the dehydrating units employed.

The heat exchange or transfer unit, as is better illustrated in Figures 3 to 5 inclusive of the drawings, comprises a casing consisting of a pair of side walls 59 and 60 which are connected along their opposite marginal edges by means of the end walls 61 and 62 and this casing is supported by means of casters or rollers 70, which latter are mounted for travel within the tracks 52 carried by the side walls 3 and 4 of the main casing, in order that this heat exchange unit may be inserted within or withdrawn from the housing or casing for the unit. The end walls 61 and 62 are provided with a plurality of vertically extending and equally spaced slots 63. The respective slots within these end walls are in alignment and their upper ends are opened, whereby one or more tubes 64 may be inserted through the upper opened ends of the slots 63 and be totally supported by the end walls 61 and 62 of the unit casing.

These tubes 64 are preferably made from thin heat conducting metal and are of a rectangular configuration in cross section. The outer ends of each tube have secured thereto headers 65 which by means of bolts or similar fastening elements 66 are detachably connected to the outer faces of the end walls 61 and 62 of the unit casing.

Arranged within each tube 64 are fins 68 of honeycomb construction for effecting a larger wiping surface for the air as it passes through the interior of these tubes, whereas, a plurality of spaced fins or plates 67 are formed with the outer face of each tube, which latter provide additional vertical wiping surfaces for the air and moisture passing thereover and thereby making a better approach of the temperatures of the airs passing through and over the tubes. Any number of these tubes 64 may be arranged in superimposed relation within the slots 63 of the supporting casing or a stack of two tubes

may be employed, as is illustrated in Figures 1, 3, 4 and 5 of the drawings, but in any event, the tubes are retained in spaced relation to one another forming unobstructed and vertically extending moist air ducts 69 therebetween. The fins or dividers 67 extend from one side of each tube 64 and are positioned within and across the ducts 69, whereby these wet air ducts are divided into several channelways D, E and F opened at their upper and lower ends.

The tubes 64 may all extend entirely through the end walls 61 and 62 of their supporting casing, as illustrated in Figures 8 and 9 of the drawings, or tubes of shorter length may be placed upon these longer tubes, as is illustrated in Figures 1, 3, 4 and 5 of the drawings, but in this latter case, a supplemental wall 71 similar to the end wall 62 is secured to the side walls 59 and 60 of the supporting casing, whereby the supplemental wall 71 will act as a support and holder for one end of each of the tubes which are of shorter length. In the form of heat exchange unit as shown in Figure 7 of the drawings, the tubes of greater length are supported upon the tubes of shorter length, but the tubes of shorter length have each only two sets of plates or dividers 67, whereas, the longer tubes are provided with five plates 67. From this arrangement, it will be obvious from Figures 1 and 3 of the drawings that the ducts 69 are so divided by means of the plates 67 as to form six rows of vertically extending channelways and in these channelways is arranged suitable moisture holding material 72 such as excelsior or the like for retaining or retarding within the several channelways of the ducts 69, the flow of water from the troughs 40 as it flows through the several channelways of the ducts 69 into the sump 10.

By mounting the heat exchange unit upon the rollers or casters 70, it may be readily and easily inserted through the opening 53 of the main casing into the heat casing or, when required, it may be removed therefrom, whereby, access may be gained for cleaning the ducts 69 between the tubes of the unit or replacing excelsior therein, as may be required. Each tube 64, being of the same construction and design, is interchangeable and, therefore, may be readily replaced or new tubes substituted therefor should they become worn or need repairs. The lower ends of the first row of fins or plates 67, that is, the row of plates 67 that are positioned adjacent the wall 61 of the casing therefor, may have projections extending therefrom or a plate 73 attached thereto, which latter projects within the sump 10 and its lower end is arranged below the water line 43 forming a sealed closure between the duct 36 and several of the channelways of the ducts 69 within the heat exchange unit, whereby, the incoming air may pass from the duct 36 into the first channelways D between the tubes 64 and, finally, be drawn into the moist air duct 25. Other deflectors or baffles 74 may be connected to the heat exchange unit for directing the flow of air to the several channelways of the ducts 69.

In this preferred form of the invention as shown in Figures 1 to 6 inclusive of the drawings, the raw (fresh) outer air or a mixture of this outer air and reconditioned air from the area being air-conditioned may enter the main casing 1 through the duct 24.

As the exhaust fans or blowers arranged within the casing 29 and 34 are set in motion, this outdoor air will be drawn through the duct 24 where it may pass over the dehydrating agents supported within section A of the drum 54 or when

using the apparatus in climates where it is unnecessary to remove moisture from the incoming air, the containers 56 may be removed from the section A, whereby, the incoming air may freely pass through the perforated bottom 55 of the drum into the duct 36 where it is drawn through the filtering mat 58. As this incoming air leaves the mat 58, it is divided up into a primary stream and one or more secondary streams by means of the heat exchange unit. This primary stream of air having an established or desired dew-point is drawn through the opening 37 of the heat exchange unit casing into the lower and longer tubes 64 of the heat exchange unit and then exhaust from these tubes 64 through the opening 38 into the duct 31 in a substantially dry state, or at the same entering dew-point. This duct 31 may be of larger area than the combined area of the passageways within the tubes 64 whereby the air may be expanded. This air is then drawn through the blower casing 34 and finally discharged through the outlet 35 into the enclosure or area to be air-conditioned.

Part of the incoming air passes around the filter mat 58 and will be drawn by means of the blower mounted within the casing 29, first through the vertical channelways D, where it will come in direct contact with the moisture holding or retaining material 72 where it is cooled by evaporation, and this evaporative cooling medium will effect anhydrously a primary cooling of the primary stream of air, and then this moist air from the channelways D will pass through the opening 39 into the moist air duct 25. Other secondary streams of air will, by means of the blower arranged within the casing 29, be drawn through the opening 37 into the upper tubes 64 or tubes of shorter length. This substantially dry stream of secondary air will then discharge within the compartment 76 where it will meet with a water mist flowing from the troughs 40 and then enter the vertical channelways E between the tubes 64, where it passes through the moisture retaining material arranged therein for effecting an evaporative cooling of this stream of secondary air. From the lower ends of these channelways E, these secondary streams of air pass over the water contained in the sump 10 and enter the lower ends of the vertical channelways F arranged between the tubes 64. While passing through the moisture retaining material arranged within the channelways F, these secondary streams of air are subjected to a further evaporative cooling until they enter the moist air duct 25 through the opening 39 formed within the top of the heat exchange unit casing. As this cooled moist air passes through the duct 25, it will contact the outer surfaces of the cowl 26 for cooling the same and the dehydrating agents as they pass through this cowl. Finally, this moist air is drawn through the casing 29 and then discharged to the outside through the outlet 30.

From this arrangement, it will be apparent that these secondary streams of air as they pass through the upper tubes 64, are cooled anhydrously without increasing their moisture content and then are subjected to an adiabatic evaporative cooling. These secondary streams of air while passing through the channelways F will cause to effect anhydrously the second stage of cooling to the primary stream of air as it passes through the longer tubes 64 and these secondary streams of air as they flow through the channelways E will effect anhydrously an-

other and more intense cooling of the primary streams before they leave the tubes 64.

By employing this multi-pass heat-transfer unit, air may be cooled to the wet-bulb temperature of the secondary stream of air, without the aid of any supplemental cooling or refrigerating equipment. Furthermore, by arranging the shorter tubes upon the longer tubes and providing the channelways D, E and F between these tubes, an effective counterflow of the secondary streams of air about the primary streams is established without coming into direct contact with the latter. The streams of wet secondary air passing through the channelways D will naturally pick up more heat (because of the temperature difference) than each of the succeeding sections or channelways E and F, so that by the time the dry primary streams of air have reached the ends of the tubes 64, the wet passages on the outside of these tubes will have brought the temperature of the primary streams of air to a point or degree approaching the wet-bulb temperature of the wet streams of secondary air at that point.

When it becomes necessary to use the multi-stage, self-regenerating dehydrator, the entering air as it is drawn through the duct 24 passes downwardly through the section A of the drum 54 where it comes into contact with the hygroscopic compositions arranged therein and moisture taken from this air, and the amount of moisture so taken is controlled by giving an intermittent rotary motion to this drum whereby when the saturation point of the compositions has been reached in section A, the latter may be moved and assume the position of section B within the hot air duct 21, the section B will then assume the position of section C within the cooling chamber of the cowl 26 and the section C will assume the position of the section A within the duct 24, whereby a fresh or regenerated supply of the hygroscopic composition will be presented to the incoming air. This rotary intermittent movement is given the drum 54 as often as is required in order to maintain a desired or established dew-point before the incoming air enters the heat exchange unit. By absorbing moisture from this incoming air, its dry-bulb temperature will rise, its dew-point caused to drop and its wet-bulb temperature will remain substantially constant. After a sufficient amount of moisture has been picked up by the compositions in this section A, this latter section is caused to be moved into the duct 21 over a gas burner 18 arranged therein, where heat will be applied to the dehydrating agents to force them to give up the absorbed moisture. This moisture will leave through the stack 22 together with the products of combustion. At the same time this "drying up" of the dehydrating agents by heating is taking place, the section C that has moved into the duct 24 will be absorbing moisture from the incoming air stream. When the section C is ready to be moved into duct 21, the section A will be dry and ready to move into the cooling chamber within the cowl 26 where the dehydrating agents carried thereby will be dry cooled. The wet air stream in duct 25, however, will be considerably cooler than the reheated section A entering the chamber of the cowl 26 and this latter will serve as a conductor of heat for carrying the latter from the section A into this wet air stream for outside discharge. The action upon the section A while in the duct 24 is for the latent heat of condensation to be given out, this heat caused by the condensation of moisture absorbed by the de-

hydrating agents while in the duct 24. The action in that section A while in the duct 21 is to put back into the moisture absorbed by the dehydrating agents, the latent heat of vaporization that was given off in duct 24 and thus cause the moisture in these dehydrating agents to evaporate, drying the dehydrating agents. Practically, however, it will have added a considerable amount of extra heat to cause it to give up its moisture. It is therefore desirable to cool this heated section in order to remove this excessive heat over and above the amount taken by the latent heat of vaporization in evaporating the moisture out of the dehydrating agents. Obviously, these cooled, dried dehydrating agents can be used again and the process repeated as often as required. Also, any number of these sections A, B and C may be employed and the axis of rotation in any direction may be effected to accomplish the desired results. Furthermore, it is even possible to accomplish these results by only employing two sections within the drum 54; in the one section, let the moisture be absorbed by the dehydrating agents and in the other section reheat these dehydrating agents to force them to give up the moisture contained therein, from where it could again be moved into contact with the incoming air to pick up more moisture as required. This latter method would have the natural tendency to increase the dry-bulb and wet-bulb of the air passing through the reheated section and would, therefore, make a larger cooling load for the first stages of the heat-transfer unit to pick up. However, any means for dehydrating air by means of a dehydrating agent, with provisions made for the regeneration or reactivation of the dehydrating agent within the same unit or enclosure, and with means for regenerating, re-activating, heating and/or cooling, may be employed.

When employing the preferred form of apparatus as an air heating unit, the containers for the dehydrating compositions are removed from the section A of the drum 54 and the air blower within casing 29 remains stationary, whereby the upper end of the moist air duct 25 is dampered shut. The blower within the casing 34 is brought into use whereby a stream of air is drawn through the duct 24 into the duct 36, where it is filtered after passing through the mat 50. This stream of air is then drawn through the longer tubes 64 and after passing through the duct 31 is forced to enter the enclosure to be air heated through the outlet 35. The pump 45 is also set in motion, whereby the water from the sump 10 may be elevated within the troughs 40 from where it may flow by gravity through the channelways D, E and F and settle again within this sump 10. Arranged within the compartment 11 is a gas burner 17 or similar heating unit which is employed for heating the water within the sump 10 and the particles of combustion from this compartment 11 can pass through the duct 23 and escape through the chimney 22. This heated water as it passes through the heat exchange unit, will obviously raise the temperature of the air passing through the tubes 64, whereby the heated dry air may be used for heating the enclosure connected to the outlet 35.

From the above, it is apparent that I can produce a compact apparatus which will be comparatively inexpensive to build, operate, and maintain, which will operate efficiently irrespective of the weather or water conditions where installed and one in which cool conditioned air

may be supplied to a home, room or other enclosure when required and, further, one which may be used for heating a home, room or other enclosure.

Figure 7 of the drawings presents a modification of the apparatus hereinbefore described. This modification consists of the same cubical casing and arrangement of walls as disclosed in the previous apparatus. In this present apparatus, the air is drawn into the air inlet duct 24 and through the dehydrating drum where the moisture is absorbed therefrom to give the air a definite dew-point. The air continues from the drum through the air filter 50 where it is divided up into a primary stream and secondary stream 10 as it passes into the multi-pass heat exchange unit. The primary stream of air passes through the longer tubes of the heat exchange unit, into the duct 31 in a manner which is substantially similar to that of the principal apparatus. In this modification, the heat exchange unit has its shorter tubes at the bottom of the longer tubes which are in the top position, or in the inverse order of the similar heat exchange unit as previously described. Positioned beneath the vertical channelways G is a sump 10 containing water, which sump is provided with a ball valve for controlling the level of the water therein from an outside source of water. A pipe system 18 is connected to said sump and runs upwardly and above wet channelways G to supply water to distribution trays mounted across the top thereof. A water pump 19 is mounted within pipe system 18 for giving the liquid therein an upward lift. Beneath wet channelways H is a second sump 80 separated from the first sump 10 by wall 81. Pipe 82, which is connected to an outside source for supplying liquid, passes through said first sump in such a manner as to be surrounded by the liquid therein and continues on into said second sump where a ball valve controls the flow of liquid from the pipe 82 to maintain a definite level within said second sump. Water is drawn from said second sump by pump 90 connected thereto. Said pump 90 then forces the water upwardly through pipe 83 to the distribution troughs above the wet channelways H. Wet air exhaust duct 25 has mounted therein a dividing wall 84, which dividing wall continues from the exhaust fan casing 29 downwardly to the top of the heat exchange unit casing to completely separate the flow of air and liquids of wet channelways G from wet channelways H. The wall 14 has an opening formed therein which is normally closed by means of a pivotally mounted door 85, which latter when opened to the dotted position shown closes that section of the moist air duct leading from the channelways H of the heat exchange unit and permits blower 34 to draw moist air through opening at 14 when desired for adding moisture to conditioned area.

In the operation of the device, the incoming air in duct 24 has a portion thereof passing around the filter mat 50 and continuing downward to a point directly beneath wet channelways G and is caused to travel upwardly therethrough by means of the wet air exhaust fan. This secondary stream of air which has not been dehydrated meets the flow of water coming downwardly from the water distribution trays above wet channelways G and it immediately absorbs considerable moisture, which absorption lowers the dry-bulb temperature thereof to the temperature of the water, or the original wet-bulb

of the air, whichever is the lowest, while at the same time, the air by its absorption causes the water to be cooled by evaporation. This cooled water and air which is passed between the horizontal tubes cools, by conduction, the dry primary stream of air passing horizontally through the same. The secondary stream of air passing through the shorter tubes opens into a chamber 86 with substantially the same dew-point but with a lower wet-bulb and dry-bulb temperature than it had upon its entrance to the tubes of the heat exchange unit. This air in chamber 86, which is a secondary stream of air, passes upwardly towards and through wet channelways H and in so doing, is met by water coming down from the water distribution trays thereabove. This secondary stream of air with its lowered wet-bulb temperature absorbs the moisture and is cooled thereby to its new wet-bulb temperature, while at the same time, the air cools the water by evaporation. This secondary stream of air passing upwardly through wet channelways H further cools the primary stream of air passing through the longer tubes to the duct 31. The wet stream of air passing through channelways G passes on upwardly around the cowling for cooling the dehydrating drum and on out into the atmosphere outside of the enclosure being conditioned. The other moist stream of air passing upwardly through wet channelways H is of a lower temperature than said first wet stream and it is therefore desirable to separate it from said first stream by means of wall 84. If it is desirable to further humidify and slightly cool the air within duct 31, then door 85 can be swung open to guide the second stream of air into said duct 31, inasmuch as said door acts as a damper to stop the flow of air thereby. By separating the channelways G from the channelways H, the temperature of the liquid within channelways H can be considerably lowered and, therefore, the air passing therethrough can be correspondingly cooled to a lower point. By this arrangement, the effect of counterflow can be obtained as hereinbefore described.

When it is desired to use the apparatus for heating a room, the gas burner 11 below said first sump is placed in operation and thereby heats the liquid therein. By conduction, the liquid in said sump heats the liquid within pipe 82, whereby the liquid within said second sump is also caused to be heated upon receiving the heated liquid from said pipe 82. By opening door 85, without pump 90 being in operation, the air leaving shorter tubes 88 will be partially humidified by heated water in sump 80, and will pass upwardly through H, through opening at 14, into blower 34 for discharge into enclosure being air-conditioned. If additional humidification is required, pump 90 feeding pipes 83 from heated water in second sump 80 can be operated intermittently and automatically to furnish any humidity required while door 85 is opened as described. It will be found, however, that this procedure will be very seldom required, and pump 90 will usually operate only during the cooling season.

Another modification of the original apparatus is disclosed in Figure 8. This modification is quite similar to the original apparatus described, except that a heat transfer unit instead of having superimposed tubes of different lengths as is better illustrated in Figures 1 and 5 consists of tubes 64 which are all of the same length,

through which passes the primary stream of dry air, while the spaces between said horizontal tubes form vertical ducts which correspond to the moist air ducts 69 as are better illustrated in Figure 5 divided into as many channelways as may be required by means of the fins the same as those fins 67 as are better illustrated in Figures 3 and 5 of the drawings carried by one side of each of said tubes and extending across the space between each pair thereof. As in all of the heat exchange units comprising part of the present invention, excelsior or other moisture absorbing substances may be placed in the vertical or wet channelways of the heat exchange units.

In the present modification, the air enters the air inlet duct 24, passes through the dehydrating drum 54 where its dew-point is set by the absorption of the moisture therefrom and passes on into air filter 87. The air then passes from air filter 87 directly through the tubes of the heat transfer unit, where, upon leaving said heat transfer unit, it is met by a cooling and humidifying mat 88, which will be better described hereinafter. A second stream of air enters within casing 1 through slots 89 from the outside of casing 1 and is drawn upwardly and around the water sump 10, up into the vertical or wet channelways of the heat exchange unit where this incoming stream of air is met by a downcoming stream of liquids from the water distribution trays above the heat transfer unit. This upgoing air is cooled by absorbing moisture and at the same time, lowers the cooling point of said water by causing the evaporation thereof and also lowers the temperature of the air in the tubes 64. Both the air in the tubes 64 and in the wet channelways have their dry-bulb temperatures lowered to the temperature of the cooled water or the wet-bulb temperature of the air in the wet section, that is, whichever is the lowest. The wet stream of air passes upwardly through the duct 25 around the cowling 26 and thereby cools said dehydrating drum and passes on outwardly into the atmosphere through the outlet 30 beyond the enclosure being cooled. The dry stream of air up leaving the heat transfer unit and in passing through the cooling and humidifying mat 88 is both cooled and has moisture added thereto and passes on upwardly through duct 31 past the exhaust blower in casing 34 and through a further means 90 positioned within the duct 31 for further cooling and dehumidifying air as much as possible from where the air passes out into the space 91 being cooled, where it causes a circulation of the air therein and finally passes outwardly through a return duct where it may, if desired, return to air inlet duct 24.

The wet, cool stream of air passing outwardly through the wet air exhaust duct 30 can pass by and through a condenser 92 of a refrigerating unit mounted across said duct 25. This condenser is thereby cooled by conduction as the cool air passes therearound. The refrigerating unit coupled to said condenser may be used to cool the air passing through the air distribution duct, as for example at 90.

In this modification, it is to be noted that both exhaust fans are operatively coupled to one motor 93 and in this manner, the cost of a second motor is eliminated, as well as having the operation cost of the twin blowers lowered.

In the winter operation of the present device as in other modifications, the gas burner 77 below the sump is operated to heat the liquid in the sump and thereby heats the water. This

heated water passing downward from distributor troughs serves as the means whereby the air within the dry tubes 64 of the heat transfer unit is heated. The cooling and humidifying mat 88 is supplied with liquid from a sump 94 directly therebeneath by means of a water circulation pump 95 and pipe 96. This second sump 94 receives its liquid from pipe 97 which has passed through said first sump 10 from a water supply system and the liquid within said second sump whose height is regulated by a ball valve upon the end of said pipe 97 is thereby heated. As the air from the dry tubes 64 of the heat transfer unit passes through said mat 88, it has the heated moisture added thereto. This heated and humidified air passes out through the blower into the space to be heated. Of course, where it is necessary to add moisture to the air within duct 31, the dehumidifying drum 54 is not placed in operation and, conversely, where it is necessary to take away moisture from the air coming inwardly through the air inlet duct, said dehydrating drum is operated to absorb the moisture therefrom, whereas, no liquid is passed downwardly through said mat and, therefore, the air within duct 31 will retain the same dew-point as the air which entered the heat transfer unit or both the dehumidifying drum and the mat used in such a manner that a low dew-point is first obtained for cooling purposes and then the air is humidified by the mat.

Figure 9 is quite similar to Figure 8 but shows an apparatus which has eliminated the dehydrating apparatus and which receives its primary stream of air directly to within the casing through an air cleaner 98 and the secondary stream of air through openings 89. The operation of the apparatus of said Figure 9 is for the most part shown similar to that of the apparatus of Figure 8 but is somewhat more economical to build and is efficient for dry atmosphere where, at times, it is only necessary to humidify and not dehumidify the air being treated.

A further form of apparatus is shown in Figure 45 10 for carrying out the method of conditioning air as described in the previous modifications. As shown, a cubical casing having an opening formed in one side thereof for the entrance of air to points within the casing, supports therein 50 the apparatus necessary for conditioning the air as desired. Directly within this casing and interposed between said opening and an air blower is an air filter 99. Said air blower is operatively connected by belt 100 to a motor 101 for causing the rotation of the blades of said blower. In line 55 and connected to the exhaust end of said air blower is a heat exchange unit 102 for cooling or heating air as desired. Positioned directly beneath said heat exchange unit is a water sump 103 which has a water inlet pipe controlled by a float valve 104 positioned therewith. Directly beneath said water sump in turn is positioned a gas burner 105 or other heating means. Pipe system 106, which has a water pump 106' interposed therein, has one end thereof mounted within said water sump 103, while the opposite end is mounted above a series of water distribution trays 106'' arranged within the wet air exhaust duct 107 directly above wet channelways of the heat exchange unit 102. The water circulating pump 106' is rotated by means of a belt 108 connected to the rotating axle of said air blower and is so operated thereby as to draw liquid from the sump 103 and lift it vertically to the water distribution trays through said pipe system.

Said heat exchange unit 102 has a lower opened end hood 109 which directs a primary stream of air to the tubes 64 thereof from said air blower and a secondary stream of air is directed by means of the deflectors or baffles 110 to the vertical channelways arranged between the tubes 64 of the heat exchange unit. The entrance to the tubes of the unit is entirely enclosed, whereby the primary stream of air is guided, with the aid of baffles extending from the unit proper, to within of these horizontal tubes. The horizontal tubes of the unit carry on one outer side thereof vertical fins, which fins are extended at their lower end outside of the exchange unit proper to form curved baffles 110 for guiding the secondary stream of air upwardly into the heat exchange unit into the sections formed by the fins and horizontal tubes. Directly above the wet channelways of the secondary stream of air is the wet air exhaust duct 107 for guiding the wet air to any point outside of the casing or enclosure being conditioned, preferably to the outdoors. The dry tubes 64 of said heat exchange unit has an air distribution duct 111 extending therefrom for directing the treated air to within the room being conditioned and mounted within said air distribution duct at a point close to said casing is a mat 112 for further cooling and humidifying the air when desired. As shown, means is provided by way of a pipe 113 for distributing water to said mat from pipe 106. The flow of this water is suitably governed by a solenoid valve 114 or like means, which may be set to permit water to spray down to within the mat which comprises excelsior or other moisture absorbing material situated within a casing having two faces thereof formed with a series of small openings for permitting air to go through the excelsior and thereby receive moisture for cooling and humidifying the said air. Positioned directly beneath said mat and connected thereto by an opening formed in said air distribution duct 111 is a suitable drain 115 for gathering the liquid dropping from said mat and conveying the same to said water sump. In the operation of the present device where it is desired to cool air, said motor is placed in operation, whereby the blades in said air blower are caused to rotate and the said water pump is also rotated. In this manner, air is drawn through the air filter 99 where it is cleaned and drawn into the air blower where, in turn, it is discharged through the exhaust opening thereof. The upper portion of the air coming from the blower passes upwardly and is guided by the said baffles into the horizontal tubes of the heat exchange unit where it passes on through the mat into the air distribution duct. The secondary stream or lower stream of air from the blower is guided by the baffles 110 upwardly through the wet channelways of the heat exchange unit. This secondary stream of air is met by downwardly falling water coming from the water distribution trays and absorbs part of this moisture and has its dry-bulb temperature lowered to the temperature of the water or to the original wet-bulb temperature of the air, whichever of the two is the lowest. At the same time, this upwardly moving air cools the downwardly flowing water by causing the evaporation of a portion thereof. This cooled wet stream of air cools the primary stream of air by conduction through the passage of the secondary stream of air and the water around the fins and the horizontal tubes. The wet stream of air continues on upwardly into the air exhaust duct on out to

some remote point. The primary stream of air which has been cooled without direct contact with the secondary stream of air has therefore had no moisture added thereto. If this air is drier than desired, the solenoid valve or like means will permit water to be distributed over said mat, whereby the air passing through the excelsior which has absorbed said water will be humidified to the point desired and will at the same time be cooled. The passage of the dry air around the moist excelsior causes evaporation of the water and this moistening of the dry air will lower its dry-bulb temperature and will also cool the water remaining in the mat. By placing the water in an absorbing mass, such as excelsior, less water is required to effect the humidifying and cooling, inasmuch as the same moves downwardly at a slower rate than a stream of sprayed water. This slow downward movement of the water permits it to be more readily cooled, inasmuch as more air can pass thereover than if the water were moving at a faster rate. Therefore, it is obvious that a mat of the type described is economical to operate with better results than by spraying or using other means for distributing the water throughout the passage of the air.

When it is desired to use a unit as just described for heating a room, the gas burner below the sump is operated to heat the liquid within the sump and the wet air exhaust duct is suitably closed. The air forming the primary stream will be heated due to the passage around the horizontal tubes and between the fins of the heated liquid from the water distribution trays. Further, the water supply for said humidifying mat will be a branch of pipe system 106, connecting the same through said branch pipe to said sump pipe system and thereby the water delivered to said mat will be heated. The amount of moisture here imparted to the air may be suitably controlled by means of humidostat in conditioned area controlling operation of solenoid valve 114.

The unit as just described is economical to operate due to the fact that only one motor is necessary and there are a smaller number of rotating members than in any of the previously described apparatuses. Apparatus of this type is extremely economical to construct and as is obvious, will have approximately the minimum in operation cost.

In Figure 11 of the drawings is disclosed a second unit wherein only one air blower is required. In this apparatus, a cubical casing having an opening formed in one side thereof has interposed between the inlet opening of the air blower and said opening of the wall, an air filter 116 for cleaning the air. At the exhaust opening of the air blower is positioned and carried thereby suitable tubing for dividing the air emerging therefrom into a primary and secondary stream of air. As shown, a section 117 of said tubing extends downwardly to a heat exchange unit 118. The upper portion 119 of said tubing extends upwardly, then horizontally and then downwardly to a point directly over said heat exchange unit. A second piece of tubing 120 which is connected to a wet air exhaust duct 121 emerging from the top of said cubical casing, extends at right angles to said duct horizontally, then vertically downward and then horizontally. Said first tubing 119 of the secondary stream of air passes between and through and is thereby surrounded by said vertical section of the second piece 120 of tubing of the secondary stream.

Positioned directly beneath said heat exchange unit is a liquid sump 122, while further positioned beneath said sump is a heating means 123. As in Figure 10, a water pump 124 is interposed within a pipe system connected at one end to said sump and at the other end to water distributing means 128 and is driven by the rotating axle of said air blower. Connected to and extending from the exhaust end of said heat exchange unit is an air distribution duct 125 for distributing the air to within an area being conditioned. In said distribution duct is positioned a suitably arranged water sprayer 126 which has liquid supplied thereto through a water pump 127, driven by a motor, which pump receives its liquid from within said first sump or from its own individual sump, not shown, whose level can be suitably controlled by a ball valve.

In the operation of the present apparatus, said motor causes the air blower to suck air in through the air filter and opening in said casing. Said blower then forces the air outwardly through its exhaust opening where it is met by the upper and lower system of tubing. The air passing into the lower system or primary stream passes through a heat exchange unit of a construction similar to the heat exchange unit of Figure 10. That is, this primary stream of air passes through horizontal tubes out into an exhaust duct 125 where moisture may be added thereto by the operation of the water spray 126 or if the moisture content of the air is sufficient, then said water spray is not necessary. The secondary stream of air which passes up into the first portion 119 of the tubing for conveying the same is cooled as the said tubing passes between and through the horizontal and vertical sections of the second portion of the tubing. This cooled dry air having a low dry and wet-bulb temperature passes around the water sprays 128 directly over the heat exchange unit where it absorbs moisture and is lowered to its new wet-bulb temperature where it continues into the second section of the tubing and passes therethrough on out into the wet air exhaust duct. The wet cooled air in the second section of the tubing cools the air in the first section by conduction. The secondary stream of air in passing around said water sprays 128 and in lowering itself to its new wet-bulb temperature also lowers the moisture to a temperature equivalent to the new wet-bulb temperature of the air. The portion of the moisture not absorbed by this secondary stream of air drops downwardly through the fins and around the horizontal tubes of the heat exchange unit and thereby cools the primary stream of air by conduction. By the continuous operation of the present device, the secondary stream of air by its movements and absorption of moisture continues to lower its dry-bulb temperature to a new 60 wet-bulb temperature. By this procedure, the primary stream of air is cooled to a point wherein its new dry-bulb temperature is equivalent to its entering dew-point temperature. It is to be noted that the secondary stream of air passes 65 in opposite directions and at right angles to itself and the hereinbefore described effective counter-flow means for cooling the air is obtained.

When it is desired to raise the temperature instead of lowering the same, the heating means 123 below the sump may be placed in operation and thereby heated water caused to drop downwardly around the heat exchange unit for heating the primary stream of air. Similarly, the heated water may be passed to the spraying means 70 75

in the water distribution duct or may be used for heating the pipe supplying the water to said spray, whereby air within said water distribution duct can be humidified, if desired, and heated to the actual temperature of the water within the sump.

The heat exchange units of the devices hereinbefore described may have the outlet ends of the dry passages restricted and the inlet ends 10 of the wet passages similarly restricted. The restrictions may be by baffles placed at these points or by forming these ends of the tubes, forming the passages, smaller than the remaining portions thereof. However, when the heat exchange 15 unit passages are thus restricted, the air should be blown into the dry passages thereof and in view thereof, air blowers, as shown in Figs. 10 and 11, should be mounted in passages 36 of the devices shown in Figs. 1 and 7. The blowers 34 20 will then be unnecessary and undesirable and should be eliminated. By this arrangement, air will be pushed through the dry passages and due to the restriction at the outlet thereof, a partial compressing of the air will take place. Upon 25 the air escaping from the dry passage into the conduits leading to the area to be air-conditioned, the air will be expanded. However, when the inlet openings of the wet passages are restricted, 30 it is necessary to draw the air therethrough by air exhaust fans 29, as in Figs. 1, 7 and 8. This drawing will create a pressure drop or partial vacuum within the vertical wet passages, causing moisture to more readily evaporate in these wet passages and thereby afford a better cooling 35 to the dry passages by this adiabatic expansion within said wet passages.

The essential principles upon which all of the foregoing apparatuses are operated are essentially the same with minor variations at different 40 points. It is to be understood that the applicant considers it well within his invention to change the positions of the dehydrating unit, the heat exchange unit, the air blowers or the cooling and humidifying mat to different positions with- 45 in the apparatus, where the operation of the apparatus so arranged produces a conditioned air.

Manifestly, the construction herein shown is capable of considerable modification and such modifications as come within the scope of my 50 claims, I consider within the spirit of my invention.

I claim:

1. The method for air-conditioning an enclosure consisting of dehydrating a body of air until a desired dew-point for the air is established, cooling a portion of said air by evaporative cooling with a liquid, using said cooled portion of air to anhydrously cool the remaining portion of said air, then cooling a portion of said remaining portion of air by evaporative cooling with a liquid to its resultant lowered wet-bulb temperature, using said moist cooled portion of said remaining portion of the air to anhydrously cool the relatively dry remaining portion of air, continuing the foregoing steps until said relatively dry remaining portion of air has its dry-bulb temperature lowered to a desired degree, the lowermost point of which is solely defined by the degree at which the wet-bulb temperatures of those portions of the air have been cooled by evaporation with a liquid and then distributing this cooled air whose dew-point has been kept constant into said enclosure for mixing with and replacing the air therein.
2. The method of conditioning air which com-

prises the steps of dehumidifying a stream of air, dividing said dehumidified stream of air into a primary stream and a plurality of secondary streams, conducting said primary stream of air through a heat exchange unit and then to a point of utilization, separately reducing the temperatures of said secondary streams of air by evaporative cooling with liquids, causing one of said cool, moist bodies of secondary air to pass directly through said heat exchange unit for anhydrously cooling said primary stream of air and causing the moist bodies of the remaining secondary streams of air to flow in counter directions through said heat exchange unit for further anhydrously cooling said primary stream of air.

3. An apparatus for conditioning air comprising a cubical casing having an air inlet opening, partitions arranged within said casing for establishing a pair of spaced chambers communicating with said inlet opening, a filter mat arranged within one of said chambers, a heat exchange unit arranged within said casing between said chambers, means for drawing a primary stream of air through said inlet opening, filter mat, heat exchange unit and chambers to a point of utilization, means for drawing a secondary stream of air through said inlet opening and said heat exchange unit, evaporative cooling means arranged within said casing including said secondary stream of air and means for causing said

secondary air stream to flow in counter directions through said heat exchange unit whereby said secondary air stream will be in heat exchange relation with said primary air stream at separate points while the latter passes through said heat exchange unit.

4. An apparatus for conditioning air comprising a cubical casing having an air inlet opening, a dehumidifying unit supported within said casing and adapted at times to project within the air inlet opening thereof, partitions arranged within said casing to form a pair of spaced chambers, a heat exchange unit arranged between the chambers formed within said casing, means for drawing a stream of air through said inlet opening, dehumidifying unit, heat exchange unit and said chambers, means for dividing said stream of air after it passes said dehumidifying unit into a primary stream and a plurality of secondary streams, evaporative cooling means arranged within said casing including said secondary streams of air whereby said secondary streams of air while passing through said heat exchange unit will be brought into heat exchange relation with said primary stream and means for causing each individual stream of secondary air to be separately directed through and exhausted from said heat exchange unit.

GENARO A. LARRIVA.
